United States Patent [19]

Freeman

[11] Des. 244,820

[45] June 28, 1977

[54] COMBINED TV, STEREO AND ACCESSORY CABINET

[76] Inventor: Leroy C. Freeman, 5964 Streamview Drive, San Diego, Calif. 92105

[] Term: 7 Years

[21] Appl. No.: 625,589

[22] Filed: Oct. 24, 1975

[51] Int. Cl. .... D6—05

[52] U.S. Cl. D6/186

[58] Field of Search .... D6/158—186,
D6/4; D56/4 C

[56] References Cited

U.S. PATENT DOCUMENTS

D. 185,708 7/1959 Herrmann D6/164

D. 186,115 9/1959 Church D6/164
D. 189,041 10/1960 Knudsen D6/164
D. 232,608 9/1974 Darrow ..... D6/164 X

Primary Examiner—Bruce W. Dunkins
Attorney, Agent, or Firm—Carl R. Brown

[57] CLAIM

The ornamental design for a combined TV, stereo and accessory cabinet, substantially as shown and described.

DESCRIPTION

FIG. 1 is a perspective view of a combined TV, stereo and accessory cabinet, showing my new design;
FIG. 2 is a perspective view from the other end thereof, with the sliding doors in another position;
FIG. 3 is a front elevational view therof, with the sliding doors in another position; and
FIG. 4 is a rear elevational view thereof.

Fig. 1

Fig. 2

Fig. 3

Fig. 4